Fig. 4

Fig. 5

Fig. 6

Fig. 7

Fig. 8

FIG. 1 is a perspective view in folded position of a combined envelope and sheet for advertisement showing my new design, the back not shown being plain and unornamented;

FIG. 2 is a front plan view in unfolded position;

FIG. 3 is a view similar to FIG. 2 with the right panel folded inward;

FIG. 4 is a view similar to FIG. 3 with the left panel also folded inward;

FIG. 5 is a view similar to FIG. 3 with the left panel folded backward; and

FIG. 6 is a view similar to FIG. 5 showing a modified form of my new design.

FIG. 7 is a view similar to FIG. 5 showing another modified form of my new design;

FIG. 8 is a view similar to FIG. 5 showing yet another modified form of my new design; and

FIG. 9 is a view similar to FIG. 5 showing still another modified form of my new design.

The dash lines indicate perforations.

I claim:

The ornamental design for a combined envelope and sheet for advertisement, as shown and described.
